UNITED STATES PATENT OFFICE.

BENJAMIN F. MCGUINESS, OF SAUNDERSVILLE, MASSACHUSETTS, ASSIGNOR TO CROMPTON & KNOWLES LOOM WORKS, OF WORCESTER, MASSACHUSETTS, A CORPORATION OF MASSACHUSETTS.

SHUTTLE-PLACER AND THREAD-CUTTER FOR LOOMS.

1,261,417.

Specification of Letters Patent.

Patented Apr. 2, 1918.

Application filed August 18, 1916. Serial No. 115,608.

To all whom it may concern:

Be it known that I, BENJAMIN F. MCGUINESS, a citizen of the United States, residing at Saundersville, town of Grafton, 5 in the county of Worcester and State of Massachusetts, have invented a new and useful Shuttle-Placer and Thread-Cutter for Looms, of which the following is a specification.

10 This invention relates to a combined shuttle placer and thread cutter designed for use upon weft replenishing looms. In such looms it is essential that the shuttle shall always occupy substantially the same 15 position in the shuttle box at the time when a weft carrier is to be transferred in order that the fresh carrier may be accurately inserted in the shuttle jaws.

Different arrangements have been proposed for securing this result. Many 20 different forms of shuttle checks and binders have been proposed for accomplishing this purpose, but they have not proved entirely satisfactory, and have usually largely increased the power required to run the loom. If the pressure of the binder is reduced so 25 as to permit a light pick it has been found impossible to stop the shuttle in the same position on every pick. It has also been proposed to provide a shuttle placer for pushing the shuttle into the box to a definite 30 position. Such placers have usually been actuated from the cam shaft, and have operated every time the shuttle entered the 35 shuttle box. This positioning operation is not necessary except at the time of transfer, and this method of operation on every pick has caused unnecessary wear of the parts without any useful result.

40 It is the principal object of my present invention to provide a shuttle positioning device or shuttle placer which shall be operative only after a transfer is indicated, and which shall then operate with great accuracy and certainty.

With this object in view, I provide a shuttle placer which operates in conjunction with the transfer mechanism whereby when the transfer mechanism is actuated 45 the shuttle placer is correspondingly rendered operative.

A further object of my invention is to provide an improved and simplified thread cutter for use in conjunction with the shuttle

placer. In the preferred form this thread 55 cutter is mounted upon the shuttle placer and is movable therewith, the operative movement of the cutter being derived from the movement of the shuttle placer.

Another feature of my invention relates 60 to the provision of improved devices for gripping and cutting the thread, and for thereafter slackening the thread prior to the operation of the temple thread cutter.

I further provide a combined shuttle 65 placer and thread cutter which also acts in itself to revoke the transfer of the weft carrier if the shuttle stops so far out of the box that the shuttle placer cannot correct its position.

70 Further objects of my invention relate to certain arrangements and combinations of parts which will be hereinafter described and more particularly pointed out in the appended claims.

75 A preferred form of my invention is shown in the drawings in which—

Figure 1 is a front elevation of certain parts of a loom with my improved mechanism mounted thereon;

Fig. 2 is a side elevation of the mechanism shown in Fig. 1;

Fig. 3 is a detail plan view of the shuttle placer and its swivel support;

Fig. 4 is a perspective view of the shuttle 85 placer with the thread cutter mounted thereon, and

Fig. 5 is a detail sectional view of the thread cutter, taken along the line 5—5 in Fig. 2.

90 Referring to the drawings I have shown a portion of the breast beam 10 of a loom having a weft replenishing magazine 11 mounted thereon. The magazine is provided with a transference arm 12 mounted 95 upon a fixed pivot 13 and provided with a member 14 movable vertically into and out of the path of an actuator or bunter 15, carried by the lay 15a. A shaft 16 is mounted in bearings on the end of the magazine, 100 and is provided with fingers 17 each adapted to move a slide 18 vertically. Each slide is provided with a pawl 19, which is adapted, in the position shown in Fig. 1, to engage an arm 20 secured to a shaft 21, and to give 105 said shaft an angular movement as the slide descends.

An arm 22 is also fixed to the shaft 21,

and has a slot and pin connection with a bell crank 23 which is connected by a rod 24 to the member 14 pivoted on the transferrer arm. The shaft 21 is moved in the 5 direction of the arrow *a* in Fig. 1, when the substantial exhaustion of weft upon the active weft carrier is indicated and such movement will raise the member 14 to operative position.

10 All of the parts thus far described together with the mechanism, not shown, for actuating the shaft 16 are of the usual type, and form no part of my invention. For a complete description of this mechanism reference is made to the patent to Ryon, No. 1,030,748, issued June 25, 1912.

15 My improved shuttle placer comprises a cam plate 30 (Fig. 1) pivoted upon a stud 31 (Fig. 3) secured in a swivel head 32 20 rotatably mounted in a bracket 33 integral with or rigidly secured to the magazine 11. A shuttle placer 34 is secured by a bolt and slot connection to the lower end of the cam plate 30 and the plate is also provided with 25 an arm 35 which is yieldingly connected to an arm 36 fixed to the shaft 21.

30 The yielding connection comprises a link 37 (Fig. 2) pivoted to the arm 35, and having a lateral projection 38 (Fig. 1) at its upper end. A rod 39 extends through the projection 38, and is threaded at its upper end into a head 40 pivoted to the arm 36.

35 A spring 41 surrounds the rod 39 and is held thereon by check nuts 42 (Fig. 2). The parts 37 and 40 are thus yieldingly secured together in such a way that the arm 36 will act positively in the downward direction, but yieldingly in the opposite direction.

40 The cam plate 30 is provided with a cam slot 43 which is straight in its lower portion and sharply curved in its upper portion. A long cam roll 44 (Fig. 2) is mounted in bearings 45 upon the transferrer arm and extends through the slot 43.

45 The operation of the parts thus far described is as follows:—When the shaft 21 is turned, upon the indication of a transfer, the arm 36 through the link 37 raises the arm 35 and thus swings the shuttle positioner to the position shown in dotted lines in Fig. 2. The flat side surface of the shuttle positioner is then adjacent the end of the shuttle. As the lay moves forward and the bunter 15 engages the member 14 the 50 transferrer arm descends. The cam roll 44 traversing the slot 43 swings the cam plate 30 and the shuttle placer 34 to the right as soon as the downward movement of the transferrer arm begins. This movement 55 brings the shuttle placer against the end of the shuttle and forces the shuttle into its desired position.

60 As the lay continues to move forward, the back wall of the shuttle box will engage the shuttle placer 34 and will swing it forward

(to the right in Fig. 2). This movement returns the shuttle placer and the shaft 21 to their original positions, thus resetting the mechanism. If, however, the shuttle is so far out of the box that it cannot be positioned by the shuttle placer the side of the shuttle will engage the placer 34 moving it to the right, and resetting the shaft 21, but this movement will take place before the engagement of the member 14 by the bunter 15 and the transfer will be revoked. I thus utilize my shuttle positioning member as a resetting device, and also as a revoking device, without providing additional or separate devices for these necessary purposes. 75 80

When the device acts as a revoker it will be swung by the shuttle to an abnormal position to the right (Fig. 2) but such movement is permitted by compression of the spring 41 under the offset portion 38 of the link 37. 85

In the preferred embodiment of my invention I combine with the shuttle placer, above described, a new and improved thread cutting device. This device comprises a corrugated gripping jaw 50 pivoted at 51 to the shuttle placer 34, a coöperating corrugated gripping block 52 loosely mounted upon the shuttle placer 34, a knife blade 53 fixed to the shuttle placer and a knife blade 90 54 pivoted at 51 and mounted to move with the pivoted jaw 50. The gripping block 52 is held in position by two studs 55 extending loosely through holes in a flange 56 formed on the shuttle placer 34. Cross pins 57 limit the downward movement of the studs 55 and the block 52, and coil springs 58 force the jaw yieldingly downward. 95 100

A link 60 (Figs. 1 and 2) is pivoted at its lower end to the jaw 50 and at its upper end is slidable in a swivel collar 61 pivoted at 62 to an arm 63 (Fig. 3) integral with the swivel stand 32. A collar 64 (Fig. 2) is fixed to the link 60 and engages the lower side of the collar 61, and a spring 65 encircles the link above the collar 61 and is pressed against said collar by a collar 66 secured to the upper end of the link 60. As the shuttle placer swings to rearward or operative position the link 60 swings about the pivot 62. 110 The resulting change in the relative position of the different centers opens the jaw 50, swinging it to the position shown in dotted lines in Fig. 2, in which position it is well adapted to engage and grip the outgoing 115 weft. As the shuttle placer is thereafter moved forward toward its original position the jaw is closed, gripping the thread against the upper block 52 and cutting the thread between the knives 53 and 54. 120 125

As the transferrer arm returns to its extreme raised position the shuttle placer and the thread cutter are swung to the left as viewed in Fig. 1. This movement occurring after the severing of the thread slackens the 130

thread between the thread cutter and the selvage, which in certain classes of goods is found to be of material advantage.

From this description it will be seen that 5 I have provided an extremely simple shuttle positioning and thread cutting mechanism controlled by the weft detecting mechanism, and directly operated by the transferrer arm. I have also provided for resetting the mechanism without the use of any extra parts 10 and upon occasion the shuttle placer itself acts also as a revoker.

Having thus described my invention it will be evident that changes and modifications 15 can be made therein by those skilled in the art without departing from the spirit and scope thereof as set forth in the claims, and I do not wish to be otherwise limited to the details herein disclosed.

20 What I claim is:—

1. In a loom, in combination, a member effective to operate both as a shuttle placer and as a shuttle feeler, means to move said member rearwardly across the path of the 25 shuttle when a transfer is indicated, means to thereafter move said member to longitudinally position a misplaced shuttle, and devices mounted on said member for gripping a thread and for thereafter cutting the 30 thread, said devices being actuated by the rearward and forward movement of said member.

2. In a loom, a combined shuttle placer and feeler and a thread cutter mounted 35 thereon, said cutter comprising a pivoted corrugated gripping jaw, a spring-pressed corrugated gripping block co-operating therewith, a knife blade fixed to said placer, and a second knife blade movable with said 40 pivoted jaw.

3. In a loom, a magazine, transfer mechanism therefor, weft controlled indicating mechanism for said magazine, a shuttle placer, connections controlled by said indicating mechanism and independent of said transfer mechanism effective to give said placer an initial movement to operative position upon indication of weft exhaustion, and connections through which said transfer mechanism thereafter gives said placer an operative movement to position the shuttle before the fresh weft carrier is inserted.

4. In a loom, a magazine, transfer mecha-

nism therefor including a transferrer arm, 55 weft controlled indicating mechanism for said magazine, a shuttle placer, connections controlled by said indicating mechanism and independent of said transfer mechanism effective to give said placer an initial 60 movement to operative position upon indication of weft exhaustion, and connections through which said transfer mechanism thereafter gives said placer its full operative movement to position the shuttle during the initial downward movement of said transferrer arm.

5. In a loom, a shuttle placer, devices operative with the weft replenishing mechanism for actuating said placer to position a 70 misplaced shuttle, and a lay having a portion positioned to engage said shuttle placer as the lay approaches its forward limit of movement and effective to restore said shuttle placer to normal inoperative position 75 after the shuttle is positioned thereby.

6. In a loom, a member effective to act both as a shuttle placer and as a shuttle feeler, means to normally hold said member out of the path of the shuttle, weft-controlled means to move said member rearwardly into position to engage the end of said shuttle, means to thereafter give said member a movement along the path of said shuttle to positively force the shuttle into 80 the shuttle box, and connections through which said member is operative to revoke the transfer upon engagement of said member with a misplaced shuttle.

7. In a loom, a shuttle placer normally 90 held out of the path of the shuttle, a thread cutter mounted thereon comprising both gripping and cutting devices, actuating devices effective to move said placer rearwardly into position to engage the end of 95 the shuttle and to thereafter move said placer longitudinally to box the shuttle, means to close said gripping and cutting devices successively, and means to move said placer forward to inoperative position, 100 said actuating devices thereafter moving said placer longitudinally to its original position, thereby slackening the thread held by said gripping device.

In testimony whereof I have hereunto 105 affixed my signature.

BENJAMIN F. McGUINNESS.
